UNITED STATES PATENT OFFICE.

JOHN T. WHITEHOUSE, OF CLEVELAND, OHIO, ASSIGNOR TO THE VAN DORN IRON WORKS COMPANY, OF CLEVELAND, OHIO, A CORPORATION OF OHIO.

JAIL-DOOR-LOCKING MECHANISM.

Application filed June 9, 1926. Serial No. 114,722.

This invention relates to jail door locking mechanism particularly adapted for application to the jail doors of a row of jail cells, the locking mechanism of each door being controlled from a common point from which the doors of the row may be selectively and positively locked, unlocked, opened or closed.

The invention comprises generally improvements upon the locking mechanism set forth in detail in my Patent 1,543,140, of June 23, 1925, to which reference may be had for features referred to herein merely in a general way.

Specifically this invention has for its object, the provision of additional means for securing the door or doors automatically in closed or open position and yet for selectively releasing such of the doors as it is desired to move.

Referring now to the drawings, Fig. 1 shows a jail door and portion of a similar door of an adjoining cell in closed position, together with a complete unit for the manipulation thereof; Fig. 2 is a detail of the mechanism with the door in closed position the lock having just been released; Fig. 3 is a similar detail but with the door locking in fully open position; Fig. 4 is a section along the line 4-4 of Fig. 3; Fig. 5 is a section along the line 5-5, Fig. 3, and Fig. 6 is a detail in elevation of a portion of the control panel, showing two of the control levers.

Reference numerals in the drawings correspond in so far as possible with those appearing in the above designated patent.

While the drawings illustrate the complete mechanism for control of but a single door, and reference hereinafter is generally made specifically to the various parts of a single unit, it will be understood that this is but a typical unit of the invention and that any number of doors may be so controlled in a similar manner as will be obvious from the following specification.

The general arrangement of parts as shown in Fig. 1 embraces a row of cells 4, four facing upon a common corridor sepa-

rated from the warden's room by a door not shown, but secured by the bolt 1 controlled by the handle 2. The handle 2 together with the control mechanism for all of the doors is enclosed in a lock box 3. The cell doors are arranged to slide open or closed, being supported upon hanger members 10, mounted with the side plates 9, upon rollers 8 movable along a suitable track 7 extending along each cell.

Adjacent the tracks 7 are similar tracks 110 and extending the entire row of cells is a pull bar 102 upon which are spaced at unit intervals of each cell width, gap nuts 101 supported on rollers 109 running on a track 110. The operating end of the pull bar is connected to a rack 111 whereby the pull bar may be longitudinally moved a distance equal to the door width in the following manner.

Within the lock box 3 is mounted a pinion 119 rotatable by means of a lever 121 to actuate the vertical rack 118. The upper end of this rack meshes with another pinion 117 in operative connection with a crank 116 and connecting rod 115 extending therefrom to a pinion 113, resting upon the rack 111 and in mesh with the fixed rack 114; raising of the lever 121 thus accomplishing through the mechanism described movement of the pull bar with its gap nuts, to the right Fig. 1, and vice versa.

Means having thus been provided for imparting lateral movement to the gap nut 101, across the cell, a coupling means between the gap nut and the door carriage is all that is necessary to impart the same movement to the door; and it will be obvious that by making such a coupling means for each door, controllable at will, upon manipulation of the lever 121 to produce reciprocation of the gap nuts 101, together with the proper manipulation of the individual coupling means, any or all of the cell doors may be moved to open or closed position as desired.

The coupling means employed is generally similar to that set forth in detail in my patent above referred to. Movable with each of the carriages 9 is a wedge bolt 98 sup-

ported from above by a roller 97 movable along a wedge strip 93. The gap nut embraces a recess 100 between two shoulders 103 and 104, the necessary width being such as to accommodate the bolt 98, which however, is controlled as to height, by the position of the wedge strip 93. The wedge strip is supported at one end upon an arm 200 of a bell crank pivoted at 91; and the opposite end of the wedge strip is provided with a cam 94 adapted to co-operate with a roller 95. In the lowest position of the wedge strip, upon motion of the gap nut to it, obviously the bolt 98 will ride over the intervening projection 103 or 104 and enter the recess 100; upon counter-clockwise movement of the bell crank however, the wedge strip is moved to the left and at the same time by action of the cam 94 will assume the position shown in Fig. 3, with the bolt raised to clear the gap nut; and it will be obvious that in an intermediate position of the wedge strip the bolt will project downwards sufficiently to clear the projection 104 so that the door may be caused to move only toward closed position.

The wedge strip is controlled by a lever 40 pivoted in the lock box in an inner compartment formed by the face plate 3^b and provided with a handle projecting through a slot in the face plate. The lever is connected by a rod 41 with a chain 42 passing over a pulley 42^a and connected through a pull rod 42^b with a second chain 42^c terminating at the lever 43. The lever 43 is mounted upon a vertical shaft 44 engaged at its lower end by a lost motion connection with a shaft 25 which controls locking means engageable with the bolt 34 of the door; and extends at its upper end into the tripper case 45. Upon the top of shaft 44 is mounted a lever connecting with the end of the pull rod 48 connecting through the chain 90 with the arm 201 of the wedge strip actuating bell crank pivoted at 91. Due to the mechanism just described downward motion of the lever 40 imparts upward motion to the wedge strip; the position of the lever at 40° corresponding with that of the bolt 98 in the notch 100, Fig. 2; the lever at 40°^b corresponding with the position of the bolt, Fig. 1, and the position at 40°^a of the lever corresponding with the bolt in Figs. 2 and 3.

55 The bracket 96 which carries the roller 95 carries also a bell crank 124 the lower member of which is engageable with an adjustable bolt 125 upon the door carriage, to cause an elevation of the free end of the wedge strip by a pin carried by the upper end of the bell crank and upon which a projecting finger of the wedge strip rests. The normal position of this lever being shown in Fig. 3, as the door completes its closing movement the bell crank raises the wedge

strip as described and thus raises the bolt 98 clear of the projection 103, the parts assuming the position shown in Fig. 1. Thus after closing the door the gap nut may either be retained in its position of engagement with the bolt providing an additional locking means for the door in closed position, or the entire pull bar may be returned to the right to pick up and close another door.

75 The shaft 44 is resiliently urged in a clockwise direction (looking downward, Fig. 1) by a spring within the tripper case 45, and its position is controlled by the door locking mechanism in the casing 19. The force of the spring is sufficient to overcome the weight of the lever 40 and rod 41 so that the lever is normally supported in its position by that of the door locking mechanism.

80 The door hanger 10 carries a plunger 78 which, as the door assumes a closed position, strikes a member within the tripper case 45 to compress a coil spring so that in closed position the door is normally urged to open position against the locking means in engagement with the staple 34. When it is desired to open the locked door, the proper lever 40 is lowered to the position of 40°; this motion, through connection of the lever with the shaft 44 releases the staple 34 and the spring referred to acting through the plunger 78 gives the door a slight start sufficient to clear the casing 19. Thereupon, upon releasing the lever it will return to the position of 40° where it is suspended, being positioned by the position of the shaft 44 in unlocked position of the mechanism within the casing 19.

85 What has thus far been described, is old in the art, being merely a résumé of the mechanism set forth in detail in my prior patent above referred to.

90 According to the present invention I have provided additional locking means for securing the door in either closed or open position as follows:

95 Secured above each jail door unit of the mechanism described, as appears in Figs. 2 and 3, is a bracket 505 in which are pivoted two oppositely and longitudinally extending 115 detent members 503 and 504, their downward motion being normally limited by their ends extending in the bracket. Upon the wedge bolt 98 is secured a dog or abutment member 501 adapted for co-operation with 120 the detents in a manner to be described.

125 The dog 501 is cammed upon its upper surface, which is aligned with the detent 503 so that the dog proceeds to the free end of the detent as the door reaches open position, and provides a means for temporarily raising the detent to allow it to drop to the position shown in Fig. 3 as the door completes its opening movement. In this position of the parts the downwardly extending mem-

bers upon the detent, clearly shown in Fig. 2, by abutting engagement with the dog 501 positively secure the door. The lever 40 being then moved to the locked open position 5 of 40^a the gap nut 101 may be moved to the left Figs. 1, 2 and 3 to close another of the doors or pick up another door to open it.

When it is desired to close the door illustrated, the lever 40^a is moved upwards to the locked position, lowering the bolt 98 to an elevation to enter the notch 100 in the gap nut in which position the dog 501 is clear of the detent 503. Thereupon to positively close the door it is merely necessary 15 to move the gap nut to the right sufficiently to engage the wedge bolt and then return the gap nut, and the door with it to closed position.

Movable with the door and secured upon 20 one of the side plates 9 is an upwardly extending finger or abutment 502, its upper extremity being bent as appears in Fig. 4 to the plane of the detent member 504. As the door reaches closed position the detent 25 504 being of the proper length is engaged by it and drops behind the finger 502, to lock the door in this position.

When the lever 40 is again moved downward to unlock the door, the upward motion 30 of the bolt 98 carrying the dog 501 raises the detent 504 to clear the finger 502, whereupon the door may be moved to open position as described.

It will be noted that nothing in my present invention interferes with the prior functioning of the doors coupled by the selector levers with the gap nuts 101 to be positively closed or opened; it being possible to positively close or open any or all of the doors 40 at the will of the operator of the control mechanism with the lock box 3.

What I claim is:

1. In a jail door mechanism, a door slidable on a track, a reciprocable member, a bolt movable with said door and adapted for separate movement to engagement with said member for sliding said door, means for controlling the engagement of said bolt with said member in all positions of said door, a 45 pair of detents adapted to engage members movable with said door to lock said door in fully open or closed position thereof, said door being releasable from either of said detents by movement of said bolt.

2. In a jail door mechanism, a door slidable upon a track, a reciprocable member, a bolt movable with said door and adapted for separate movement to engagement with said member for sliding said door, means for controlling the engagement of said bolt with said member in all positions of said door, a dog secured upon said bolt, a detent extending in the path of said dog in raised position of said bolt and adapted to secure the same, and therefore said door in open position 55

thereof, said dog being clear of said detent upon positioning of said bolt to engagement by said reciprocable member.

3. In a jail door mechanism, a door slidable upon a track, a reciprocable member, a bolt movable with said door and adapted for separate movement to engagement with said member for sliding said door, means for controlling the engagement of said bolt with said member in all positions of said door, a dog secured upon said bolt, a detent extending in the path of said dog in raised position of said bolt and adapted to secure the same, and therefore said door in open position thereof. 70 75 80

4. In a jail door mechanism, a door slidable upon a track, a reciprocable member, a bolt movable with said door and adapted for separate movement to engagement with said member for sliding said door, means for controlling the engagement of said bolt with said member in all positions of said door, a detent adapted to engage a member movable with said door to secure the same in closed position thereof, and means carried by said bolt to release said member. 85 90

5. In a jail door mechanism, a door slidable on a track, a reciprocable member, a bolt movable with said door and adapted for separate movement to engagement with said member for sliding said door, means for controlling the engagement of said bolt with said member in all positions of said door, an abutment member movable with said door, a detent adapted to engage said abutment member in closed position of said door to lock the same, said detent being releasable from said abutment member by movement of said bolt. 95 100 105

6. In a jail door mechanism a door slidable upon a track a reciprocable member, a bolt movable with said door and adapted for separate movement to engagement with said member for sliding said door, means for controlling the engagement of said bolt with said member in all positions of said door, a dog secured upon said bolt, a detent extending in the path of said dog in one position of said bolt and adapted to secure the same, and therefore said door, in open position of the latter, said bolt being movable to clear said dog from said detent. 110 115

7. In a jail door mechanism, a door slidable upon a track, a reciprocable member, a bolt movable with said door and adapted for separate movement to engagement with said member for sliding said door, means for controlling the engagement of said bolt with said member in all positions of said door, a dog secured upon said bolt, and a detent extending in the path of said dog in one position of said bolt and adapted to secure the same, and therefore said door, in open position of the latter when said bolt is in said one position. 120 125 130

- 4
8. In a jail door mechanism, a door slide-
able upon a track, a reciprocable member, a
bolt movable with said door and adapted for
separate movement to engagement with said
member for sliding said door, means for con-
trolling the engagement of said bolt with
said member in all positions of said door,
an abutment member movable with said

door, a detent adapted to engage said abut-
ment member to secure the door in closed 10
position thereof, and means carried by said
bolt to release said detent from said abut-
ment member.

In testimony whereof I hereby affix my
signature.

JOHN T. WHITEHOUSE.
